CLAIM

The ornamental design for a console for van vehicles, as shown and described.

DESCRIPTION

FIG. 1 is a right side perspective view of the console for van vehicles hereof showing my new design;

FIG. 2 is a left side perspective view thereof;

FIG. 3 is a top plan view thereof;

FIG. 4 is a left side elevational view thereof;

FIG. 5 is a bottom view thereof; and,

FIG. 6 is a top plan view thereof with the top lid shown in open condition.

The broken line showing of environment is for illustrative purposes only and forms no part of the claimed design.
